United States Patent Office.

TRUMAN MERRIAM AND ALANSON G. ALLEN, OF WATERLOO, WISCONSIN.

Letters Patent No. 64,021, dated April 23, 1867; antedated April 19, 1867.

IMPROVEMENT IN STEAM GENERATORS.

The Schedule referred to in these Letters Patent and making part of the same.

TO ALL WHOM IT MAY CONCERN:

Be it known that we, TRUMAN MERRIAM and ALANSON G. ALLEN, of Waterloo, in the county of Jefferson, and State of Wisconsin, have invented a new and useful Improvement in Steam Generators; and we do hereby declare that the following is a full, clear, and exact description of the same, reference being had to the annexed drawings, making part of this specification, in which—

Figure 1 is a perspective view.

Figure 2 is a transverse vertical section.

Figure 3 is an end elevation partly in section.

Figure 4 is a longitudinal section.

The same letters are employed in the different figures in indicating identical parts.

A is the fire-box for wood or coal, which we make of cast iron, (with the tubes hereinafter described,) cast in the body of the plates, sustaining detachable cast-iron plates, B, which are made with perforations or in form of lattice-work, so as to retain fire-clay, with which they are coated on the inner surface, where exposed to the heat. On these sides, forming the top of the furnace, we place the tank C, which receives the cold water, and in which it is heated before being pumped into the boilers. Across the open space in the fire-box, above the fire and below the tank, is placed a series of cast-iron cylinders, of suitable strength for resisting the pressure of the steam. These cylinders may, however, be made of boiler plate if preferred. These cylinders are placed in successive tiers, with spaces between them for the free passage of the draught. They are connected by pipes, E' and F', which are cast or otherwise constructed in the end plates of such cylinders, or they may be formed by grooves in the end plates and other plates tightly fastened to such end plates; but as such, caps will then form, in fact, part of the end plates; and as these forms of construction are substantially identical, we shall claim both under the general expression, pipes formed in the end plates of the cylinders. The boilers E are connected by pipes E' with the two cylinders F, placed immediately above them, and each of these is connected by a pipe, F', with the cylinder above it, and so on as far as the series may be carried. The steam thus heated to any required degree is taken from the upper tier of cylinders to the engine. A force-pump may be placed on the lead pipe if desired, to qualify the temperature of the steam by ejecting small quantities of hot water into the dry steam, or by ejecting oil to lubricate the cylinders of the engine, or the reduction may be made in the second set of cylinders adjacent to the set described. The pipes H conduct the hot water from the tank C to the force-pump I, by which it is forced through the pipes K into the boiler E, which boiler or cylinder contains two copper evaporating troughs, X, set one above the other, so that the water thrown by the pumps shall fall upon the upper one, run its length, and, falling upon the second one, traverse also its length, being converted into steam by contact with the heated troughs. Should any water not be vaporized, it will fall upon the highly heated surface of the cylinder and be at once converted into steam. The pipes passing from the pumps to the boiler we cast in the plates forming the walls of the fire-box, in coils, so as to receive additional heat in passing from the pump to the boilers. In the drawings we show two sets of tiers of cylinders, to each of which belongs a force-pump; the pipes K respectively passing through the fire walls of the furnace on the side nearest the boiler to which they lead. L L are blow-off cocks attached to the boilers E E. D is the smoke-stack. The heat rising from the fire, passing freely around the respective cylinders, the steam therein is superheated and dried, and the series of tiers should be continued as long as they can be used for utilizing any portion of the heat evolved by the combustion of the fuel.

What we claim as our invention, and desire to secure by Letters Patent, is—

1. The combination of the cylinders E F G, arranged in successive tiers above the furnace, and connected by pipes formed in their end plates with a corresponding set of similar cylinders, into which the steam is passed from the first set, and in which it is tempered by the introduction of water or oil, substantially in the manner and for the purpose set forth.
2. The perforated or latticed metallic walls of the furnace, when constructed and arranged substantially as set forth.
3. The arrangement of the tank C, induction pipe H, pump I, eduction pipes K, and the furnace walls, substantially as set forth.
